US0D1033334S

(12) **United States Design Patent** (10) Patent No.: **US D1,033,334 S**
(45) Date of Patent: ** Jul. 2, 2024

(54) **BATTERY PACK**

(71) Applicant: **LG Chem, Ltd.**, Seoul (KR)

(72) Inventors: **Yeo-Joo Choi**, Daejeon (KR);
Bum-Hyun Lee, Daejeon (KR); **Jae-Ki Lee**, Daejeon (KR); **Jae-Bum Lim**, Daejeon (KR); **Gyeong-Su Jeong**, Daejeon (KR); **Seok-Hyun Hong**, Daejeon (KR)

(73) Assignee: **LG Energy Solution, Ltd.**, Seoul (KR)

(**) Term: **15 Years**

(21) Appl. No.: **29/775,757**

(22) Filed: **Mar. 25, 2021**

(30) **Foreign Application Priority Data**

Jan. 4, 2021 (KR) 30-2021-0000212

(57) **CLAIM**

The ornamental design for a battery pack, as shown and described.

DESCRIPTION

FIG. 1 is a front perspective view of a battery pack according to our design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings depict portions of the battery pack that form no part of the claimed design.
